UNITED STATES PATENT OFFICE.

VINCENT V. VEENSCHOTEN, OF ERIE, PENNSYLVANIA.

FLUID-PRESSURE SYSTEM.

1,396,237.

Specification of Letters Patent.

Patented Nov. 8, 1921.

Application filed November 5, 1917. Serial No. 200,287.

To all whom it may concern:

Be it known that I, VINCENT V. VEENSCHOTEN, a citizen of the United States, residing at Erie, in the county of Erie and 5 State of Pennsylvania, have invented certain new and useful Improvements in Fluid-Pressure Systems, of which the following is a specification.

This invention relates to apparatus for 10 controlling fluid pressure systems, wherein such fluids as water and steam are used under varying pressures, and particularly where it is desired to maintain certain relations between the pressure of the fluid or 15 fluids in different parts of the system, or to prevent injury of the system in case of accident or other abnormal occurrences. In illustrating my invention I have related it particularly to boiler feed-water systems; 20 and one of the objects of the invention is to provide means for more completely controlling such systems, particularly in cases of excessive loads thereon or accidents thereto, or of improper manipulation of the system 25 in any way.

In boiler feed-water systems it is common 30 to use a pump for forcing the water into the boiler, the pump being operated by steam supplied by the boiler; and it sometimes happens that the pressure in the water pipe, because of breakage or leakage thereof, becomes reduced to such an extent that the pump begins to race due to the decrease in 35 its load, and injury thereto may result. Such a result may follow the reduction in suction in the supply line of the pump due to shortage of water, leakage, breakage, or otherwise. Or it may be that the pump is of insufficient capacity to supply the water required by the boiler or battery of boilers 40 under certain exigencies, such as abnormal increase in loads on the boiler. And one of the objects of the invention is to prevent injuries to the pump, or to give notice to the operator, by stopping the pump if any such an emergency arises.

Of the accompanying drawings, Figure 1 is a front elevation of a boiler system, more or less diagrammatic, embodying features of 50 my invention; Fig. 2 is an enlarged sectional view of the pump governing devices of the system; and Fig. 3 is an enlarged sectional view of the control valve, showing additional detail structure.

Referring to Fig. 1 the boiler 5 is fed with water by means of the feed-water pipes 6

and 32, the supply of water being controlled by the regulator 7, which controls, in a well known manner, the level of the elevation of the water level in the boiler by means of the 60 feed-water valve 8; the water pressure in the feed-water pipe being maintained by the pump 9, which is operated by the engine 10. The engine is supplied with steam from the boiler through the pipe 11; and the steam 65 supply valve 12 is controlled normally, in a well known manner, by the governor 13; while my control valve in the casing 14, in turn, controls the operation of the governor under certain conditions. 70

The governor 13 is what is commonly called a constant excess pressure governor and tends to maintain a constant difference in the pressures of the water delivered by the pump and the steam operating the pump. 75 As is common, the governor comprises a cylinder 15, within which is a piston 16. The piston is fixed, by the stem 17, to the steam valve plunger 18, which controls the supply of steam to the engine 10. The upper end of the cylinder 15 is connected by a pipe 19 with the feed-water pipe 32, and the lower end by a pipe 20 to the steam pipe 11; so that the water pressure tends to force the piston 16 down to close the valve 12, 80 and the steam pressure, assisted by a weight 21, tends to force the steam valve open. 85

The casing 14 of the control valve is connected in the pipes 19 and 20, and controls the water and steam pressures on the piston. 90 This control valve comprises a valve 22 which is adapted normally to close a port 23; but, under certain conditions, will be forced upward to close a port 24. Normally the water pressure is transmitted to the 95 upper side of the piston 16 through the pipe 19, the upper port 24, and pipe 25; but steam pressure will be transmitted there through pipe 20 when the valve is forced upwardly opening port 23 and closing port 24. 100

Fixed to the valve 22 is a downwardly extending stem 26 to which is fixed a secondary valve 27 which normally closes a port 28 leading to the atmosphere; and which, when forced upwardly, closes a port 29 leading to 105 the steam pipe 20. When the disk 27 is in its normal position, indicated in Figs. 2 and 3, the steam pressure acts through the port 29 and the pipe 30, on the lower side of the piston 16. Under normal operation there is 110 no operation of the valves 22 and 27, and the valve casing 14, merely transmits,

through its ports, the water and steam pressure unchanged to the governor cylinder. If, however, the water pressure above the disk 22 becomes materially less than the steam pressure on the under side of the valve 22, the valve will be forced upwardly, allowing the steam pressure to pass to the upper side of the piston 16, and shutting off the steam pressure from the lower side of the piston 10 by closing the port 29, and releasing the steam pressure in the lower end of the cylinder 15 by opening the port 28.

In operation, then, if there should be a serious leakage in the feed-water pipe, or a shortage of water in the pump suction pipe, the pressure of the water in the feed-water pipe would diminish, the water in the boiler would sink, the regulator 7 would open wider the valve 8, this would reduce still more the pressure in the feed-water pipe, and finally the valve 8 would open to its maximum extent. If other boilers were in use in parallel with boiler 5, using water from the pump 9, through the pipe 31, or otherwise, 25 their regulators would also open their feed-water valves, still further reducing the pressure in the main feed-water line 32, and hence in the pipe 19 and above the valve 22. This reduction in pressure would cause the 30 governor to open wider the steam valve 12, and racing of the pump would follow. And if, for any reason, the pressure in the feed-water pipe were reduced to a certain predetermined amount the steam would force up 35 the valve 22, and, hence, 27, closing the ports 24 and 29, opening ports 23 and 28, and thus releasing the pressure below the piston 16; the piston would then be forced down and the valve 18 would be closed; and the 40 pump would be stopped before its increased speed, due to the decreased load and the increased supply of steam to the pump engine, would become dangerous. If a great reduction in pressure in the feed-water pipe 45 should occur suddenly, by a breakage in the system or a material decrease in water supply, the water pressure would instantly fall so far below the steam pressure that the valves 22 and 27 would very quickly be operated and the pump stopped before it could 50 overrun dangerously. A check valve 33 prevents the back pressure from the boiler reaching the control valve and interfering with its operation.

55 As normally the steam in the casing 14 presses down on the valve 27 and up on the valve 22, the upward pressure would be equal to the difference; and the downward pressure on the valve 22 due to the 60 water would hold the valve closed; and the excess upward pressure necessary to open the valves would depend on the relative sizes of the valve ports and the weight of the valves and stems. In order to adjust the 65 amount of excess pressure required, any

suitable weight or spring may be used. I prefer for the purpose a spring 35 encircling the stem 36 extending upward from the valve 22, and pressing against a washer 37 resting on a shoulder 38. The position of the upper 70 end of the spring, and hence its compression, may be adjusted by means of a nut 39 threaded into a yoke 40. By these means any predetermined excess steam pressure 75 may be provided for.

In starting the pump, before the steam is turned on, the valves 22 and 27, due to gravity and the pressure of the spring 35, will always be down in normal position. When the steam valve 51 is opened there 80 will be a tendency for the steam to pass into the control valve casing; and to force the valve 22 up, and then pass into the cylinder 15 and force the valve 12 closed and stop the pump before it gets up sufficient 85 water pressure to close valve 22 against the steam pressure. To avoid this the valve 51 may be closed until the pump starts.

It sometimes may be desired to have the control valve operate when the water pressure is equal to or even greater than the steam pressure. This may be provided for by the use of any suitable means which assists, instead of opposes, the steam pressure. For the purpose I prefer a spring 45 encircling the stem 46 extending downwardly from the valve 27. The spring may be adjustably compressed between the collar 47 and the plate 48; the plate being threaded into the casing of the valve as shown in 100 Fig. 3. It is to be understood, however, that neither of the springs 35 or 45 is essential to the operation of the control valve, but are merely for use when it is desired to vary the relative or excess pressure at which 105 the valve will be operated from the pressure fixed by the relative sizes of the valve ports. Either of the springs may be used or both or neither, as may be desired.

As it is difficult to prevent leakage when 110 two valves are fixed to the same stem, the valve 27 may be arranged in any suitable manner so that it is slidable to a limited extent on the valve stem 26. I prefer in this instance to arrange the valve and stem 115 as indicated in Fig. 3 so that the valve is slidable on the section 49 of the stem, between the shoulder 50 and the collar 47, which is threaded onto the stem 46. As the steam pressure forces the valve 27 downward, it will be forced thereby into its port normally, and a little leakage when the valve is forced upward is immaterial.

I claim as my invention:

1. The combination of two vessels, a fluid 125 under pressure contained in each of said vessels, a device arranged to be operated by both of said fluids acting together, and means for controlling the operation of said device by both of said fluids when the diff- 130

- ference between the pressures thereof reaches a predetermined amount.
2. The combination of two vessels, a fluid under pressure contained in each of said vessels, means for varying the pressure of one of said fluids, a device arranged to be operated by both of said fluids as the difference between the pressures thereof varies, and means for controlling the operation of said device when said difference reaches a predetermined amount.
3. The combination of two vessels, a fluid under pressure in each of said vessels, means tending to maintain a constant difference of pressure on said fluids, means tending to vary the pressure on one of said fluids, and means for controlling said first mentioned means when said pressure difference reaches a predetermined amount.
4. The combination of two vessels, a fluid under a varying pressure in each of said vessels, means tending to maintain a constant difference in the magnitude of said pressures, means for controlling said first mentioned means when said difference reaches a predetermined amount, and means for adjusting said predetermined amount.
5. The combination of a vessel, a fluid under pressure in said vessel, a conduit having an opening into said vessel, means for forcing a fluid into said vessel through said conduit, means for governing said forcing means tending to maintain a constant excess pressure in said conduit over the pressure in said vessel, means for varying the size of said opening, and means for controlling said governing means when the said excess pressure reduces to a predetermined amount.
6. The combination of a boiler, a pump, a pipe connecting said pump with said boiler, a check valve in said pipe, a feed-water valve in said pipe, a regulator controlled by the water level elevation in said boiler for controlling the opening of said feed water valve, a governor for governing the speed of said pump, said governor being operated by the pressure of the steam in said boiler and the water in said pipe, and means for controlling said governor when the excess pressure of the water in said pipe over the pressure of the steam in said boiler is reduced to a predetermined amount, and means for regulating said predetermined amount.
7. The combination of a boiler, a pump operatively connected with said boiler, a governor normally affected by the pressure of the steam in said boiler for maintaining a constant excess pressure on the discharge water of said pump over the pressure of the steam in said boiler, and means for stopping said pump when said excess pressure is reduced to a predetermined amount, said means comprising a valve casing, an outlet in said casing, two inlets into said cas-
- ing, said outlet communicating with said governor, one of said inlets communicating with said boiler and the other with the discharge of said pump, a valve in said casing adapted to alternately connect the said inlets with the said outlet, and means for cutting off the steam pressure from said governor.
8. The combination of a boiler; a pump for supplying water under pressure to said boiler; and means for stopping said pump when the pressure on the water supplied thereby becomes materially lower than the steam pressure in said boiler; said means comprising a valve for supplying steam to operate said pump; means for operating said valve comprising a piston connected with said valve; means for transmitting said steam and water pressures respectively to opposite sides of said piston; and means for cutting off said steam pressure from one side of said piston and replacing said water pressure by said steam pressure on the other side of said piston.
9. The combination of a pump for supplying water under pressure, a source of supply of steam, a valve for supplying steam from said source to operate said pump, a cylinder, a piston in said cylinder operatively connected with said valve, a conduit connecting one end of said cylinder with the said steam supply, a conduit connecting the other end of said cylinder with the water supplied by said pump, and means operated by the said respective water pressure and steam pressure for stopping said pump, said means comprising means for cutting off the steam pressure from the one end of said cylinder.
10. The combination of a pump for supplying water under pressure, a source of supply of steam, a valve for supplying steam from said source to operate said pump, a cylinder, a piston in said cylinder operatively connected with said valve, a conduit connecting one end of said cylinder with the said steam supply, a conduit connecting the other end of said cylinder with the water supplied by said pump, and means operated by the said respective water pressure and steam pressure for stopping said pump, said means comprising means for cutting off the steam pressure from the one end of said cylinder and for releasing the steam pressure therein.
11. The combination of a pump for supplying water under pressure, a source of supply of steam, a valve for supplying steam from said source to operate said pump, a cylinder, a piston in said cylinder operatively connected with said valve, a conduit connecting one end of said cylinder with the said steam supply, a conduit connecting the other end of said cylinder with the water supplied by said pump, and means

operated by the said respective water pressure and steam pressure for stopping said pump, said means comprising means for cutting off the steam pressure from the one 5 end of said cylinder and for releasing the steam pressure therein and for replacing the water pressure in the other end of the cylinder by the steam pressure.

12. In a boiler feed-water system, the 10 combination of a constant excess pressure pump governor and a controller thereof, said controller comprising a casing having two inlets and two outlets, said outlets connected respectively with the water pressure 15 chamber and the steam pressure chamber of said governor, said inlets adapted to be connected respectively with the feed-water pipe and the steam chamber of a boiler, a valve system in said casing, said 20 valve system being operable by the water and steam pressures of the system and arranged to alternately connect said inlets with the water pressure outlet.

13. In a boiler feed-water system, the 25 combination of a constant excess pressure pump governor and a controller thereof, said controller comprising a casing having two inlets and two outlets, said outlets connected respectively with the normal water 30 pressure chamber and the steam pressure chamber of said governor, said inlets adapted to be connected respectively with the feed-water pipe and the steam chamber of a boiler, a valve system in said casing, said 35 valve system being operable by the water and steam pressures of the system, and arranged to alternately connect said inlets with the water pressure outlet, and to alternately connect and disconnect said steam 40 inlet and said steam pressure outlet.

14. In a boiler feed-water system the combination of a constant excess pressure pump governor, and a controller for said governor, said controller comprising a casing having a 45 steam and a water inlet and a steam and a normal water outlet, said steam outlet being connected with the steam pressure chamber of said governor and said water outlet being connected with the normal water pressure 50 chamber of said governor; a valve system in said casing having a movable disk arranged to close successively said water outlet against the steam pressure and against the water pressure, when said water outlet 55 is closed against said steam pressure said water inlet and water outlet being connected.

15. In a boiler feed-water system the combination of a constant excess pressure pump 60 governor, and a controller for said governor, said controller comprising a casing having a steam and a water inlet and a steam and a normal water outlet, said steam outlet being connected with the steam pressure chamber 65 of said governor and said water outlet

being connected with the normal water pressure chamber of said governor; a valve system in said casing having a movable disk arranged to close successively said water outlet against the steam pressure and against the water pressure, when said water outlet is closed against said steam pressure said water inlet and water outlet being connected, and when said water outlet is closed against said water pressure said steam inlet and water outlet being connected.

16. In a boiler feed-water system the combination of a device to be operated, and a controller of said device; said controller comprising a casing having a steam and a water inlet and a steam and a normal water outlet, and said device having a steam and a normal water inlet; said device and said controller each arranged to be operated by a differential fluid pressure; said controller 85 steam and water outlets being connected respectively with the steam and water inlets of said device; said controller steam and water inlets adapted to be connected respectively with the steam and the feed-water 90 pipes of a boiler; and a valve system in said casing arranged to alternately connect the water and the steam inlets thereof with the water outlet.

17. In a boiler feed-water system the combination of a device to be operated, and a controller of said device; said controller comprising a casing having a steam and a water inlet and a steam and a normal water outlet, and said device having a steam and a normal water inlet; said device and said controller each arranged to be operated by differential fluid pressures; said controller steam and water outlets being connected respectively with the steam and the water 105 inlets of said device; said controller steam and water inlets adapted to be connected respectively with the steam and the feed-water pipes of a boiler; and a valve system in said casing arranged to alternately connect the water and the steam inlets of the casing with the water outlet thereof, and to alternately connect the steam inlet of the casing with the steam and water outlets thereof.

18. In a boiler feed water system the combination of a device to be operated, and a controller of said device; said controller comprising a casing having a steam and a water inlet and a steam and a normal water outlet, and said device having a steam and a normal water inlet; said device and said controller each arranged to be operated by differential fluid pressures; said controller steam and water outlets being connected respectively with the steam and water inlets of said device; said controller steam and water inlets adapted to be connected respectively with the steam and the feed-water 120 pipes of a boiler; and a valve system in said 125 130 casing having a movable disk arranged to close successively said water outlet against the steam pressure and against the water pressure, when said water outlet is closed against said steam pressure said water inlet and water outlet being connected.

casing arranged to alternately connect the water and the steam inlets thereof with the water outlet, and to alternately connect said steam inlet with said steam and water outlets, and to connect said steam outlet with the external air when said steam inlet is connected with said water outlet.

19. The combination of two distinct sources of fluid pressure, a device arranged to be operated normally by both of said fluids acting simultaneously, and means for controlling the operation of said device by said fluids when the difference between the pressures thereof reaches a predetermined amount.

20. The combination of two vessels, a fluid under pressure contained in each of

said vessels, a device arranged to be operated in opposite directions by said fluids, and means for eliminating the effect of the operation on said device of one of said fluids when the difference between the pressures thereof reaches a predetermined amount.

21. The combination of two vessels, a fluid under pressure contained in each of said vessels, a device arranged to be operated by the difference of said two pressures, and means for eliminating the effect of one of said pressures when said difference reduces to a predetermined amount.

In testimony whereof, I hereunto set my hand.

VINCENT V. VEENSCHOTEN.
